(57) CLAIM

The ornamental design for a bag support member, as shown and described.

DESCRIPTION

FIG. 1 is a top perspective view of a bag support member showing my new design;

FIG. 2 is a front elevational view thereof;

FIG. 3 is a side elevational view thereof;

FIG. 4 is a top plan view thereof; and,

FIG. 5 is an enlarged cross-sectional view taken in the direction of the arrows on line 5—5 of FIG. 2.

The broken lines shown in all views are for illustrative purposes only and form no part of the claimed design.
